UNITED STATES PATENT OFFICE.

MENTLEY F. STILL, OF LAPANZA, CALIFORNIA.

CHURN.

SPECIFICATION forming part of Letters Patent No. 730,172, dated June 2, 1903.

Application filed May 22, 1902. Serial No. 108,597. (No model.)

To all whom it may concern:

Be it known that I, MENTLEY F. STILL, of Lapanza, in the county of San Luis Obispo and State of California, have invented a new and useful Improvement in Power-Churns, of which the following is a specification.

My invention relates to churns run by steam or other power and of that type of churn-body in which the churn has no separate dasher or beater, but the churning is effected by the oscillation or vibration of the churn-body itself.

My invention consists in the novel construction and arrangement of the churn-body, its supporting-frame, and actuating mechanism, whereby a simple, economical, and compact power-churn is provided in which the churn, the power mechanism, and frame are so combined as to constitute a single unitary organization, the parts being co-ordinated to and especially adapted for each other, as will be hereinafter more fully described with reference to the drawings, in which—

Figure 1 is a perspective view of the entire power-churn. Fig. 2 is an enlarged horizontal section of the engine-cylinder and its valves; and Fig. 3 is a detail perspective view of the engine-cylinder, valve-gear, and connections, the view being taken from the opposite side to that seen in Fig. 1.

In the drawings, Fig. 1, A A A A represent an X-shaped frame made of gas-pipes connected at the center by four-way couplings a , of which frames there are two, one on each side, connected at their extremities by elbow-couplings a' and cross-pipes A' . Within this frame and completely inclosed by the same is an elongated rectangular box B, forming the churn-body, which is suspended upon loop-shaped stirrups or hangers D, whose upper ends are provided with yokes d , that loosely embrace the cross-bars A' inside of the elbow-couplings a' , which latter hold the

yokes in place. The hanger-loops D are arranged to inclose the churn-body, which thus hangs suspended from the yokes d and is capable of oscillation about the points of suspension. The hangers, however, are not parallel and vertical, but are disposed at an inclination toward each other at the bottom and are retained in this relation by boxes or

bearings attached to the bottom of the churn-body. The object in having these hangers inclined in this manner is to cause one end 55 of the churn-body to descend and the other end to rise as it moves to the right and to reverse these movements when it swings to the left. This gives a more positive dash of the contents from one end of the churn to 60 the other and secures a much more rapid and effective churning of the butter.

It will be seen that by connecting the upper ends of the X-shaped pipe-frames by means of cross-pipes A' and elbow-couplings 65 a' the two frames are connected together and braced by the same cross-pipes which carry the hangers, and as the elbow-couplings are of larger external diameter than the cross-pipes such couplings form shoulders that 70 keep the yokes of the hangers in place against slipping off. The two upper members of each X-shaped frame form the support for the churn-body, and the two lower members of the X-shaped frames form the 75 legs.

From the cross-pipes A' at one side of the main frame there are extended horizontal pipe-sections A^3 by means of T-couplings a^2 , and these pipe-sections A^3 connect with 80 vertical pipe-sections A^2 A^2 by means of elbows a^3 a^3 . Between these vertical pipe-sections A^2 A^2 are detachably connected, by means of couplings R R, the pipe E' and four-way casing E, in which latter is located and 85 held a small horizontal engine-cylinder C. This cylinder is located a little below the level of the churn-body B, and the piston-rod F is by rod H connected to the bottom of the churn-body, so that the reciprocations of the 90 piston serve to impart an oscillatory motion to the churn-body. At the joint between the piston F and connecting-rod H there is attached the curved end of a slide-rod F', whose other end slides through a hole in a cross-bar 95 G, which thus acts as a guide.

The engine-cylinder C and its valve-gear are to be operated by steam, compressed air, or any other motive fluid and while being a distinct subject-matter is nevertheless related 100 to the other parts of the churn and will now be described, reference being had more especially to Figs. 2 and 3. L L are rotary valves with three-way ports. These valves

are arranged at opposite ends of a pipe M and open into opposite ends of the cylinders. These rotary valves have crank-arms K K outside their casings, which are connected by 5 rod J and operated together by a stem I, which in turn is acted upon by the churn-body with a tappet action, as seen in Fig. 1. The valve-stem extends through a perforated projection l on the bottom of the churn-body, and as 10 this churn-body oscillates it strikes against cushioned lugs o on the valve-stem on each side of the projection l and shifts the valve-stem first in one direction and then in the other in order to reverse the ports of the 15 valves L. The lugs o are cushioned with spiral springs to break the force of the blow. When the valves are in the position shown in Fig. 2, steam flows in the direction of the arrows and the piston is moved to the right. 20 When the position of the valve-cranks K and valves L is changed by the blow from the churn-body, the ports of the valves L are turned so as to reverse the flow of steam and the piston then moves to the left. M' represents the steam-inlet pipe which enters the 25 horizontal induction-pipe M between the two valves, and N represents the steam-exhaust pipe.

Having thus described my invention, what 30 I claim as new, and desire to secure by Letters Patent, is—

1. A power-churn, comprising a support-

ing-frame with hangers, a horizontal churn-body supported in said hangers within said frame and having a projection l, a horizontally-disposed engine-cylinder with piston-rod, and pitman connecting the piston-rod to the churn-body, a valve-gear for the engine-cylinder having a reciprocating rod for operating it, said reciprocating rod being arranged 35 in line with the projection l of the churn-body and extending through the same and having lugs on opposite sides of said projection adapted to be struck by the said projection on the churn-body to cause the oscillation of the churn-body to impart motion to the valve-gears substantially as described. 40

2. A power-churn comprising a supporting-frame formed of four-way pipe-couplings a, X-shaped members A, A, A, A, cross members A' with elbow-couplings a', hanger-bars D D suspended from the upper cross members A', a horizontally-disposed churn-body suspended in the hangers within the frame, the pipe extensions A² A³ at one end of the 45 frame having couplings a² a³, the engine-cylinder C and its valve-gear, and supporting-frame sections E E' with detachable couplings R R, and means for connecting the engine to the churn substantially as described. 50
